UNITED STATES PATENT OFFICE.

MICHAEL A. BURKE, OF KINGMAN, ARIZONA.

SUPPORT.

1,131,906.

Specification of Letters Patent. Patented Mar. 16, 1915.

Application filed October 27, 1913. Serial No. 797,670.

To all whom it may concern:

Be it known that I, MICHAEL A. BURKE, a citizen of the United States, residing at Kingman, in the county of Mohave and State of Arizona, have invented certain new and useful Improvements in Supports, of which the following is a specification, reference being had to the accompanying drawings.

10 This invention relates to new and useful improvements in supports and more particularly to a device for supporting a candle or other lighting means, the object of the invention being to provide a supporting device of this character which is particularly adapted for use by miners and is to be carried in the mine and can be supported in any desirable place by engaging the same with any suitable object.

20 Another object of the invention is the provision of a supporting member which is provided with means adapted for engagement with various forms of objects to support the device in its operative position.

25 A further object of the invention is the provision of a support of the above character which will possess advantages in points of efficiency and durability, is inexpensive of manufacture and at the same time is 30 simple in construction and operation.

With the above and other objects in view, the invention consists in the novel features of construction and the combination and arrangement of parts to be hereinafter more 35 fully described, pointed out in the claims and shown in the accompanying drawings, in which—

Figure 1 is a side elevation of my improved candle supporter; Fig. 2 is a top plan view; Fig. 3 is a transverse sectional view; Fig. 4 is a top plan view of the handle member; Fig. 5 is a detail perspective view of the removable supporting arm; Fig. 6 is a detail perspective view of the hook member; Fig. 7 is a detail perspective view of the candle retaining thimble; Fig. 8 is a plan view illustrating the application of my improved carbid lamp holder; and Fig. 9 is a transverse sectional view of the lamp 50 holder.

Referring more particularly to the drawings, 1 indicates the elongated body member of my improved support at one end of which is formed a handle 2, the other end thereof being tapered into a point, as shown at 3, and adapted for engagement within the

earth of the mine or in any wooden support, it being understood that the pointed end of the shank 3 is sufficiently sharp that the same will readily penetrate into any 60 wooden object. Formed integral with the body 1 is a substantially circular enlarged portion 4 which is provided with a similar shaped socket 5 and extending outwardly from the enlarged portion are the spaced 65 arms 6 which form an elongated recess adapted to communicate with the socket 5. A retaining thimble 7 is provided and is to be formed of any suitable material such as aluminum or the like and comprises a circular body formed from a single blank of material which is preferably elongated in form and rolled up to provide the circular body. One end of the blank extends beyond the other end and is slit to form the 75 outwardly projecting tongue 8, the other portion upon the opposite side of the slit being bent upon itself to form a sleeve 6' adapted for insertion within the socket 5 and thence bent rearwardly to form an arm 80 7' adapted to be arranged between the spaced arms 6. A transverse pin 8' is inserted through the arms to retain the arm 7' against longitudinal movement and a pin 9 is inserted down through the sleeve 6' and 85 the socket 5, in order to securely retain the thimble 7 in its effective position.

The body member 1 is provided upon the side opposite the enlarged portion 4 with a socket 10 in which is arranged the lower end 90 of a standard 11, the lower end of said standard being provided with a tapering lug 12 which is adapted to be inserted within said socket and having a head 13 formed thereon so as to securely retain the same in 95 position. The upper end of the standard 11 is curved upon itself and provided with a suitable curved point 14 which forms a hook member 15 adapted for engagement with any stationary object to support the body 100 member 1 in an upright position. The standard 11 is provided upon its inner side with an outwardly projecting lug 16 in which is formed a suitable opening 17 adapted to receive the lower reduced end 105 18 of the supporting standard 19. The supporting standard 19 is provided with a frame 20, formed integral with the standard and adapted to receive the standard 11 when in an upright position, as clearly illustrated 110 in Fig. 3. The standard 19 is further provided with a set screw 21 which extends

through the standard and adapted to engage with the standard 11 to securely retain the standard 19 in position and also to prevent movement on the part of the same relative to the standard 11.

The preferred form, as described above, is especially adapted for use in supporting candles, but should it be desired to use the well known form of carbid lamps in use by miners at the present time, I provide an attachment in the form of a ring 22 which is adapted to receive the tapering shank 3 of the body member 1 upon which the same is slidably mounted. Formed integral with 15 the sleeve 24 and projecting rearwardly therefrom, is a resilient bar 25, the outer end of which is bifurcated and is adapted to receive a lug 26 formed upon the outer face of the standard 11 to securely retain the 20 ring 22 in position upon the shank 3.

When using the candle support in a shaft where there is a good deal of draft and dampness and water dropping from the roof of the shaft, I provide a cover or guard 25 which is in the form of the dome shaped body, as shown at 27, and upon one side of which is formed a vertically disposed socket 28 adapted to receive the upper end of the standard 19 to which the same is removably 30 secured by means of the set screw 29. The upper portion of the body 27 is provided with an opening 30 encircled by a vertical flange having at its upper end an outstanding flange 31. A second cover 32 is provided 35 which is in the form of a circular plate supported in spaced relation with the opening 30 by means of the brackets 33 and is provided upon its periphery with the downwardly extending flange 34 which prevents 40 the draft from entering the opening 30. It will be readily apparent that while I have shown and described the thimbles 7 in the present form, they may be formed in any other desired shape and of any suitable material such as aluminum or the like. The 45 rings 22 may also be formed of any light weight material and may be removably attached to the shank 3 in any preferred manner. It will be readily apparent that the cover 27 readily protects the flame of the candle from any strong draft and at the same time protects the same from the dropping of water from the roof of the shaft. It will be seen that the supporting member may be readily 55 placed in position by inserting the tapering shank 3 into the earth at any desirable point or into any wooden structures which may be at hand, but if there is nothing at hand with which it may be engaged, the hook 60 member 15 may be used to support the device in an upright position. The device as herein shown and described is extremely simple in construction and can be manufactured at a comparatively low cost.

65 While I have shown and described the

preferred form of my invention, it will be obvious that various changes in the details of construction and in the proportions may be resorted to for successfully carrying my invention into practice without sacrificing 70 any of the novel features or departing from the scope of the appended claims.

What I claim is:

1. A device of the class described including a body member having an opening, a standard having its lower end arranged therein, a hook member formed at the upper end of said standard, a lug formed upon one side of the standard and provided with an opening, a second standard having its 75 lower end removably mounted within said opening, and a cover removably mounted upon the second standard, as and for the purpose set forth.

2. A device of the class described including an elongated body having a handle, said body being provided with an opening, a standard having its lower end mounted within said opening, a perforated lug formed upon one side of said standard, a hook at the 80 upper end of said standard, a second standard having its lower end arranged within the perforated lug, a frame carried by the second standard and adapted to receive the first standard, a cover having a socket 85 formed at one side and removably mounted upon the second standard, as and for the purpose set forth.

3. A device of the class described including an elongated body having a handle at 100 one end, a shank at the other end, a ring having a sleeve removably mounted upon the shank portion, a resilient bar formed integral with the sleeve and having an opening in its outer end, and means carried by the 105 body and adapted for engagement within said opening to retain the sleeve in position upon said shank.

4. A device of the class described including a body having a handle at one end, a 110 tapering shank at the other end, said body being provided at one side with an opening, a standard having its lower end arranged within said opening, a perforated lug arranged upon one side of the standard, a hook member at the upper end of the standard, a second standard having its lower end arranged within the perforated lug, a frame carried by the second standard and inclosing the first standard, a set screw carried by the 115 second standard and engaging the first standard, a cover provided with a socket mounted upon the second standard and a set screw carried by said socket and adapted to engage the standard, as and for the purpose set forth.

5. A device of the class described including an elongated body, an enlarged portion formed at one side thereof, the outer end of which is bifurcated to form spaced arms, 130

said enlarged portion having a socket formed therein, a split retaining thimble having an extension from one side of the slit, said extension being bent upon itself to form a sleeve adapted for insertion in the socket, thence extending rearwardly to provide an arm adapted to be inserted between the above mentioned spaced arms, and pins inserted through the arms and into the sleeve and

socket extension to retain said thimble in position.

In testimony whereof I hereunto affix my signature in the presence of two witnesses.

MICHAEL A. BURKE.
